UNITED STATES PATENT OFFICE.

GEORGE E. SCHUMAN AND ALEXANDER C. SCHUMAN, OF LOUISVILLE, KENTUCKY.

REGISTERING-MACHINE.

1,072,658.

Specification of Letters Patent.

Patented Sept. 9, 1913.

Application filed December 16, 1912. Serial No. 736,998.

To all whom it may concern:

Be it known that we, GEORGE E. SCHUMAN and ALEXANDER C. SCHUMAN, citizens of the United States, residing at Louisville, in the 5 county of Jefferson and State of Kentucky, have invented certain new and useful Improvements in Registering-Machines, of which the following is a specification.

This invention has for its object to provide in a registering machine a novel and improved device for preventing the registering dials from being carried by momentum farther than they are designed to go, and also to provide an improved transfer mechanism whereby a registering dial of a higher order is advanced one step at each complete revolution of the registering dial of the next lowest order.

The machine is operated by key-levers, 20 and in connection with the latter there is also provided a device for preventing short-stroking, the key-lever being compelled to be actuated to its full extent before it can be returned.

25 The invention also has for its object to provide improved means for preventing the simultaneous operation of two or more key-levers.

These objects are attained by a combination 30 and arrangement of parts to be herein-after described and claimed, reference being had to the accompanying drawing in which—

Figure 1 is an elevation of the invention. Fig. 2 is a plan view showing one end of 35 one of the pawls hereinafter referred to. Fig. 3 is a plan view showing the key-levers. Fig. 4 is a section on the line 4—4 of Fig. 1. Fig. 5 shows a slight modification of the ratchet-wheel hereinafter referred to.

40 In the drawing, only so much of the machine is shown as will make clear the connection of the present invention therewith, and it may be here stated that while the preferred embodiment of the invention has been 45 shown, it is to be understood that various changes in the structural details illustrated may be made without departure from the spirit and scope of the invention.

50 Referring now specifically to the drawing, 10 denotes a shaft on which is mounted a registering dial shown dotted at 11. Parallel to the shaft 10 is a second shaft 12 carrying a registering dial 13 of the next higher order. Thus, if the dial 11 is a units 55 dial, the dial 13 is a tens dial. The two shafts are supported in a suitable frame, a

fragment of which is shown at 14. On the shaft 10 is fast a ratchet-wheel 15, and a similar wheel 16 is fast on the shaft 12. The ratchet wheel 15 is operated by a pawl 17, and a pawl 18 operates the ratchet-wheel 16, whereby the shafts 10 and 12 are rotated to operate the registering dials. Spring pawls 19, engageable with the ratchet-wheels, prevent backward rotation of the 60 shafts. The ratchet-wheel 15 has a deep notch 20, and the ratchet-wheel 16 has a deep notch 21, which notches are for a purpose to be presently made clear. The frame 14 also supports a rock-shaft 22 on which is loosely 65 mounted an angle lever, the two arms of which are indicated at 23 and 24, respectively. The shaft passes through the lever at the angle thereof. The arm 24 is connected by a wire 25, or other suitable connection, to a key-lever 26. The shaft 22 carries an arm 27 which is made fast so as to swing with the shaft. The extremity of the arm has a bend 28 terminating in a laterally projecting finger or abutment 29. 70

The pawl 17 is an elongated member pivoted at one end, as indicated at 30, to the arm 27 near the extremity thereof. Above the pivot the pawl has a laterally projecting lug 31 which extends through an aperture 32 75 in the arm 27 into engagement with the extremity of the arm 23 of the angle lever. Adjacent to the pivot the pawl has a tooth 33 projecting from its edge which is opposite the ratchet-wheel 15 so as to enter the 80 notches thereof. The free end of the pawl has a reduced portion 34 forming a shoulder or abutment 35. The swing of the arm 27 is limited by stops 36 located on opposite sides thereof. That edge of the arm which is adjacent to the ratchet-wheel 15 has a tooth or 85 abutment 37 adapted to come into the path of a pin or abutment 38 carried by and projecting from one face of the ratchet-wheel 15, for a purpose to be presently described. 90 A return spring 39 is connected to the arm 27, and a similar spring 40 to the arm 24. The key-lever 26 is also provided with a return spring 41. 95

The pawl 18 is an elongated member pivoted at one end, as indicated at 42, to a swinging arm 43 at the extremity of the latter, said arm being mounted on a shaft 44 supported by the frame 14 and extending parallel to the shaft 22. Adjacent to the 100 pivot, the pawl has a tooth 45 adapted to enter the notches of the ratchet-wheel 16. 110

The arm 43 has at its extremity a bend 46 terminating in a laterally projecting finger or abutment 47. That end of the pawl which is pivoted has a return bend 48 carrying a transverse pin or rigid wire 49. The arm 43 swings between stops 50 and has on its edge, which is adjacent to the ratchet-wheel 16, a tooth or abutment 51 adapted to come into the path of a pin or abutment 52 carried by and projecting from one face of said ratchet-wheel. On the arm 27 is an ear 53 through which loosely passes one end of a rod or wire 54, and on the arm 43 is an ear 55 through which the other end 15 of said rod or wire loosely passes. On the ends of the rod or wire are heads 56. A rod or wire 57 connects the arm 43 with the next arm if another registering wheel and its actuating pawl and ratchet are employed.

20 In operation, when the key-lever 26 is depressed the angle-lever is actuated and its arm 23 pushes against the lug 31, thereby swinging the arm 27 in the same direction the arm 23 is swung and moving the pawl 17 bodily forward lengthwise in the same direction, so that the tooth 33 rotates the ratchet-wheel 15 one step. As the pressure which drives the pawl is applied above the pivot 30, the pawl tooth is held firmly 25 in the notch of the ratchet-wheel, and when the latter rotates it raises the pawl to meet the abutment 29 which is also descending. At the end of the stroke the pawl and abutment come together and firmly hold the 30 ratchet-wheel from being carried too far by its momentum. When the pawl-tooth is in the deep notch 20, the abutments 37 and 38 serves this purpose. At every complete revolution of the ratchet-wheel 15, the 35 ratchet-wheel 16 is rotated one step. This action is effected as follows: When the pawl-tooth 33 drops into the deep notch 20, the free end of the pawl 17 swings down so that the shoulder 35 comes behind the pin 49. The forward movement of the pawl 17 40 now actuates the pawl 18 also and thus operates the ratchet-wheel 16. When the pawl-tooth 33 is in the shallow notches of the ratchet-wheel 15, the shoulder 35 is 45 above the pin 49 and no movement is transmitted to the pawl 18. When the arm 27 is restored to its normal position the arm 43 is also restored through the connection 54. The parts 47, 51 and 52 have the same function as the parts 29, 37 and 38. The key-lever 55 50 55 is fulcrumed on a shaft 58, and its forward end works in a slot 59 in a plate 60 which may be a portion of the casing of the machine. The rear or tail end of the key-lever 60 is turned up slightly as indicated at 61. On the inner face of the plate 60, adjacent to one side of the slot 59, is a double rack 62, and the forward end of the key-lever carries a pawl 63 adapted to engage said rack, 65 which latter is parallel to the plane in which

the key-lever swings. The pawl is pivoted at 64 to a side lug 65 on the key-lever so as to swing transversely of the rack. On each side of the head of the pawl is a tooth 66. To the tail end of the pawl is connected a spring 67 against the tension of which the pawl swings. The pawl and rack herein described, operating in connection with the key-lever 26, are designed to prevent short-troking of the latter. The action is as follows: When the key-lever is depressed, to operate a registering dial as hereinbefore described, the pawl 63 is on the left side of the rack 62, and the rack teeth on this side slant in such a direction that the key-lever 70 cannot rise. The key-lever is depressed until the pawl passes the lower end of the rack, and the key-lever may now rise, the pawl slipping upward over the teeth on the right side of the rack, which teeth are so slanted 75 that the pawl prevents the key-lever from being depressed. Thus the key-lever cannot be depressed until a full return stroke has been made and the pawl is again at the top of the rack ready to pass down the left 80 side thereof. It will be noted that the top of the rack is inclined toward the left toothed side thereof and the end of the pawl head is similarly inclined, whereby the pawl is thrown to the left side of the rack at the 85 commencement of the downward travel of the key-lever, and the herein-described action is thus assured. The bottom of the rack is inclined upward toward the right side 90 to guide the pawl to that side.

100 Any number of registering-dial actuating devices, and a key-lever for each, may be provided, and a grand total can be obtained by having a totaling mechanism connected to a bail 68 extending beneath all the key-levers so as to be actuated thereby. Thus the totaling device will register every time a key-lever is operated. In such a machine it is necessary that every key-lever operated should complete its stroke before another key-lever is operated. The following mechanism is provided for this purpose: To the rear, and below the tail ends 61 of the key-levers 26, is mounted a rock-shaft 69 having at one end a crank arm 70 carrying a laterally projecting pin 71. The shaft 69 carries hooks 72, one hook being provided for each key-lever and the ends of the hooks being normally positioned above the ends 61 of the key-levers. On the shaft 58 is 105 pivoted an arm 73 having at one end a cam-slot 74 into which the pin 71 extends. The other end of the arm carries the bail 68.

110 In operation, when any one of the key-levers 26 is depressed, the slotted end of the 115 arm 73 swings upward, whereby, through the engagement of the pin 71 with the cam-shaped slot 74, the shaft 69 is rocked in a direction to swing the hooks 72 over the ends 61 of the key-levers after the key-lever 120 125 130

- which is being operated has passed above the path of its hook. The other hooks come down over the ends 61 of the corresponding key-levers and hold the same down so that 5 they can not be operated until released. The release does not take place until the key-lever which has been actuated returns to its normal position, the return stroke withdrawing the hooks 72 from holding position.
- 10 Thus it will be evident that no key-lever can be operated until a previously operated key-lever has completed its stroke.
- If the machine is used to register tickets it may in some cases be desirable to register 15 the money value of the tickets instead of the number of tickets sold. This can be done by only a slight change in the machine if the price of the tickets is a divisor of 100 without a remainder, for example: If the 20 price of the tickets is five cents, the units ratchet-wheel will have five deep and five shallow notches spaced alternately as shown in Fig. 5, and its registering dial will be correspondingly numbered "0" and "5" 25 alternately. The other ratchet and registering dials need not be changed.

We claim:

1. In a register, registering wheels of different orders, ratchet-wheels for operating 30 said registering wheels, said ratchet-wheels having a deep notch, pawls for operating the ratchet-wheels, swinging supports carrying the pawls, an actuating member engageable with the pawl of the lowest order, 35 said pawl having means to actuate the pawl of the next higher order when said first-mentioned pawl engages the deep notch of its ratchet wheel, a connection between the supports of the pawls for returning the support of the pawl of the higher order to its 40 normal position when the support of the pawl of the lower order returns to normal position, and means for effecting such return of the last-mentioned support.
  2. In a register, registering wheels of different orders, ratchet-wheels for operating 45 said registering wheels, said ratchet-wheels having a deep notch, pawls for operating the ratchet-wheels, swinging supports carrying the pawls, an angle-lever having one 50 of its arms engageable with the pawl of the lowest order to actuate the same, operating means connected to the other arm of the lever, the pawl of the lowest order having 55 means to actuate the pawl of the next higher order when said first-mentioned pawl en-
- gages the deep notch of its ratchet-wheel, a connection between the supports of the pawls for returning the support of the pawl of the higher order to its normal position when the support of the pawl of the lower order returns to normal position, and means for effecting such return of the last-mentioned support.
3. In a register, registering wheels of different orders, ratchet-wheels for operating 65 said registering wheels, said ratchet-wheels having a deep notch, pivoted pawls for operating the ratchet-wheels, swinging supports carrying the pawls, an angle-lever 70 having one of its arms engageable with the pawl of the lowest order to swing the support thereof and actuate said pawl, and operating means connected to the other arm of said lever, the pawl of the lowest order 75 having means to actuate the pawl of the next higher order when said first-mentioned pawl engages the deep notch of its ratchet-wheel.
4. The combination of a ratchet-wheel, a swinging support, a pivoted pawl carried 80 by the support for operating the ratchet-wheel, said pawl being actuated when its support is swung, and an actuating member engageable with the pawl to swing the support thereof and actuate said pawl, said 85 member engaging the pawl at a point to press the same into engagement with the ratchet-wheel.
5. The combination of a ratchet-wheel, a pawl for operating the ratchet-wheel, a 90 swinging support carrying the pawl, a lever engageable with the pawl to swing the support thereof and actuate said pawl, an abutment projecting from the ratchet-wheel, and an abutment on the pawl-support adapted 95 to come into the path of the abutment of the pawl.
6. The combination of a ratchet-wheel, a pawl for operating the ratchet-wheel, a 100 swinging support to which the pawl is pivoted, said support having an abutment which is in the path of the pawl, and a lever engageable with the pawl to swing the support thereof and actuate said pawl.

In testimony whereof we affix our signatures in presence of two witnesses.
